DESIGN FOR AN ILLUMINATED WREATH ORNAMENT

William James Tyson, New York, N. Y.

Application July 5, 1935, Serial No. 57,601

Term of patent 7 years

To all whom it may concern:

Be it known that I, William James Tyson, a citizen of the United States, residing in the city, county, and State of New York, have invented a new, original, and ornamental Design for an Illuminated Wreath Ornament, of which the following is a specification, reference being had to the accompanying drawing, forming part thereof.

In the drawing, Figure 1 is a front elevation of an illuminated wreath ornament showing my design, the central portion being suitable for indicia. Circumscribing the central indicia portion is an annular member having a plurality of apertures

arranged in a circle and permitting light from the interior to be visible therethrough and thrown upon the outer surface of the wreath.

Figure 2 is a side elevation of the illuminated wreath ornament shown in Figure 1.

The rear view is substantially plain.

I claim:

The ornamental design for an illuminated wreath ornament as shown and described.

Signed at the city of New York this 25th day of June, 1935.

WILLIAM J. TYSON.
